The ornamental design for an electronic device clip, as shown and described.

DESCRIPTION

FIG. 1 is a top, perspective view of a first embodiment of the electronic device clip according to the new design;

FIG. 2 is a bottom, perspective view thereof;

FIG. 3 is a front view thereof;

FIG. 4 is a rear view thereof;

FIG. 5 right side view thereof;

FIG. 6 is a left side view thereof;

FIG. 7 is a bottom view thereof; and

FIG. 8 is a top view thereof.

FIG. 9 is a top, perspective view of a second embodiment of the electronic device clip according to the new design;

FIG. 10 is a bottom, perspective view thereof;

FIG. 11 is a front view thereof;

FIG. 12 is a rear view thereof;

FIG. 13 right side view thereof;

FIG. 14 is a left side view thereof;

FIG. 15 is a bottom view thereof; and,

FIG. 16 is a top view thereof.
